KNIFE AND KNIFE HOLDING MEANS FOR VENEER LATHES

Application filed June 17, 1929. Serial No. 371,460.

Our invention relates to the knives and holding means therefor for veneer lathes.

Heretofore, the knives of veneer lathes which are from 24 to 108 inches in length and are correspondingly costly have been provided with regularly spaced bolt slots by which they are fastened to the knife bar. These bolt slots have tended to weaken the blade, have increased the cost of manufacture and prevented the re-grinding of the knife blade but a relatively short distance back from the original cutting edge, thus reducing its period of usefulness and requiring frequent replacements.

Therefore, the object of our invention is to provide an efficient and inexpensive knife holding means for veneer lathes particularly adapted to hold knives without slots firmly against being driven back on the knife bar from the impact of the knife with the work.

A further object of our invention is to provide knife holding means and a knife adapted to cooperate to cause the grip of the holding element to tighten on the knife under the influence of the latter with the work.

A further object of our invention is to provide knife and knife holding means adapted to facilitate the changing of the knife blade which was a relatively slow operation with the old slotted type of veneer lathe knife.

We obtain these objects in a veneer lathe, the combination of a knife-bar provided on one side with a threaded hole, a cooperating knife-clamping bar provided with a hole to receive a clamping bolt, the opposed faces of the knife-bar and the clamping-bar being adapted to provide an inwardly tapering wedge-shaped knife-holding space between them, a clamping bolt inserted through said hole of the clamping-bar into said knife-bar, the extremity of said bolt being provided with means for rockably engaging the clamping-bar, and a set screw threaded in said clamping-bar and bearing on said knife-bar, whereby to rock the clamping bar to clamp the knife firmly against the knife-bar.

These and other incidental features of our invention, the details of construction and mode of attachment thereof are hereinafter

fully described with reference to the accompanying drawings.

In the drawings:

Fig. 1 shows an end view of the veneer lathe and illustrates in section the knife and holding means therefor;

Fig. 2 shows an enlarged front view of the knife holding means and the knife, taken looking in the direction of the arrow 2 in Fig. 1;

Fig. 3 shows a section taken on the line 3—3 of Fig. 2; and

Fig. 4 shows a perspective view of the knife clamping bar removed from the lathe.

Referring to Fig. 1, the veneer lathe may be of any standard form and in this embodiment comprises a frame *a* supporting a log *a* from which veneer is to be cut, and a knife head *b*, the latter provided with a longitudinal recess *c*, adapted to receive one leg *d'* of an A-shape in cross section knife bar *d*. So much is more or less standard construction.

The knife bar *d* of our invention, however, is provided with a recess *e* adjacent its toe for holding a plane knife blade *f* which is tapered on both sides towards its heel. Threaded bolt holes or recesses *g* are provided in the knife bar adjacent to and in parallel alignment with the knife recess *e*.

A knife clamping bar *h* is provided, adapted to be seated in the knife recess *e* with the knife blade *f* between the former and the latter. Bolt holes *j* correspondingly arranged to register with the bolt recesses *g*, are formed in the clamping bar *h*, the bolt holes *j* having shoulders *j'* adapted to engage with the curved heads of bolts *l* threaded into the bolt recesses *g*, by which the clamping bar *h* is fastened to the knife bar *d* to clamp the knife *f* between them.

The abutting face of the clamping bar *h* is inclined slightly from its heel, thus forming with the knife bar *d* a tapered recess to receive the tapered knife blade *f*.

Set screws *p* are threaded in the heel of the clamping bar and bears against the knife bar *d*.

The tip of the clamping bar *h* is provided with a recess *q* adapted to receive a removable

section *r* adapted to protect the knife blade from the wear of the log and the pressure of the toe of the clamping bar *e*.

By this construction, the bolts *g* serve as a fulcrum for the knife clamping bar *h* and permit the latter to be rocked by the set screws *p* to hold the clamping bar firmly upon the knife over its entire surface.

Further, due to the taper or wedge-shape of the knife blade its tendency is to be held more tightly under the impact with the work. Also, to remove the knife and replace it with another it is only necessary to loosen the set screws *p* which will relieve the clamping action upon the knife, take out the old knife and insert the new knife and tighten the set screws, a matter of only a few minutes, and the lathe is again ready to operate.

We claim:

1. In a veneer lathe the combination of a knife bar of A-shaped cross section, one side of the bar provided with a recess for the knife and with threaded sockets adjacent such recess, a knife clamping bar formed to lie against said side of the knife bar, and with a head projecting into the said recess of the latter, the opposed faces of one wall of said recess and of the head of said clamping bar being adapted to provide an inwardly tapering wedge-shaped knife holding space between them, a knife correspondingly wedge-shaped in said knife receiving space, bolt recesses in said knife bar having shoulders in one side thereof, bolts having hooked heads inserted through said recesses and threaded in said bolt sockets, the hooked heads of said bolts being adapted to engage with the shoulders in said recesses to permit a pivotal action of said clamping bar relative to said bolt and said knife, and a set screw threaded into the heel of the clamping bar and bearing on said knife bar, whereby said knife is clamped firmly by the clamping bar along its entire length and close to its cutting edge against said knife bar.

2. In a veneer cutting machine the combination of a knife-bar provided on one side with a threaded hole, a cooperating knife-clamping bar provided with a hole to receive a clamping bolt, the opposed faces of the knife-bar and the clamping-bar providing a knife-holding space between them, a clamping bolt inserted through said hole of the clamping-bar into said knife-bar, the extremity of said bolt being provided with means for rockably engaging the clamping bar, and means operative to rock the clamping bar whereby to clamp the knife firmly against the knife bar.

3. In a veneer lathe the combination of a knife bar provided on one side with a recess for the knife and with a threaded socket adjacent such recess, a knife clamping bar provided with a head adapted to be inserted in said recess, the opposed faces of the head of

the knife clamping bar and the knife bar being adapted to provide an inwardly tapering wedge-shaped knife holding space, a knife correspondingly wedge-shaped adapted to be inserted in said knife receiving space, a bolt recess in said knife bar, a bolt having a hooked head inserted through said recess and threaded into said threaded socket of the knife bar, the hooked head of said bolt adapted to engage the wall of said recess, thereby to permit a pivotal clamping movement of said knife clamping bar on said bolt, a set screw threaded into the heel of the knife clamping bar and bearing on said knife bar, whereby to rock the clamping bar to clamp the knife firmly against the knife bar.
